UNITED STATES PATENT OFFICE.

RALPH E. BROWNELL, OF CHICAGO, ILLINOIS, ASSIGNOR TO WILLIAM H. DIETZ, OF SAME PLACE.

DESIGN FOR A SAVINGS-BANK.

SPECIFICATION forming part of Design No. 29,133, dated August 2, 1898.

Application filed March 25, 1898. Serial No. 675,194. Term of patent 3½ years.

To all whom it may concern:

Be it known that I, RALPH E. BROWNELL, a citizen of the United States of America, and a resident of Chicago, county of Cook, and State of Illinois, have invented and produced a new and original Design for Savings-Banks, of which the following is a specification, reference being had to the accompanying drawing, forming part thereof.

10 The figure is a perspective view of a savings-bank, showing my new design.

As shown in the drawing, the leading or material features of my design consist in a glass globe A, having an opening at its top, which globe rests upon a plate B and is capped by a substantially similar plate C, which latter plate at its center is provided with a small

aperture or slot c, communicating with the opening at the top of the globe A. Near each of the four corners of the plates B C and 20 passing therethrough, connecting the same together, is a round rod D, provided at both of its ends with a spherical knob or button E. Said rods touch or nearly touch the face of the globe.

25 Having described my invention, what I claim as new, and desire to secure by Letters Patent, is—

The design for a savings-bank as herein shown and described.

RALPH E. BROWNELL.
